UNITED STATES PATENT OFFICE.

HENRY F. FLICKINGER, OF BUCYRUS, OHIO.

RAILROAD CROSS-TIE.

SPECIFICATION forming part of Letters Patent No. 283,230, dated August 14, 1883.

Application filed April 21, 1883. (No model.)

To all whom it may concern:

Be it known that I, HENRY F. FLICKINGER, a citizen of the United States, residing at Bucyrus, in the county of Crawford and State of Ohio, have invented a new and useful Railroad Cross-Tie, of which the following is a specification, reference being had to the accompanying drawings.

This invention relates to that class of cross-ties for railroads which are made of iron; and it consists in certain improvements in the construction of the same, and of the keys for securing the rails in position upon the ties, as will be hereinafter fully described, and particularly pointed out in the claim.

In the drawings hereto annexed, Figure 1 is a perspective view of my improved cross-tie, showing the rails in position. Fig. 2 is a perspective view of one of the keys or wedges detached. Fig. 3 is a plan view of a section of track laid with my improved cross-ties. Fig. 4 is a transverse sectional view on the line *x x* in Fig. 3. Fig. 5 is a sectional view on the line *y y* in Fig. 4, and Fig. 6 is a view illustrating a modification.

The same letters refer to the same parts in all the figures.

A in the drawings designates my improved cross-tie, which may be cast or otherwise formed of iron, and which consists of the vertical web B, bottom flange, C, and top flange or head, D. The top flange or head is provided, adjoining the web, with vertical perforations E to receive the legs F of staples G, provided on their upper inner sides with flanges H, for the purpose of holding the rails and keys, as will be presently described.

The lower ends of the legs F of the staples may be screw-threaded to receive nuts I, by means of which they may be fastened securely in position, said nuts coming, as shown in the drawings, on the under side of the top flange or head, D, of the tie, where they will be well protected and out of the way; but the said

staples may be secured in position in any other 45 suitable way that may be deemed desirable or preferable.

S J are the keys, which are slightly tapering or wedge-shaped longitudinally, as shown. The inner edges of the keys have rabbets K, 50 to receive the edges of the adjoining rail-flanges, and the outer edges of the keys are adapted to fit under the flanges H of the adjoining staples G.

The operation of this invention will be readily understood from the foregoing description, taken in connection with the drawings hereto annexed. The rails are placed between the staples G, each with one flange under that of one of the staples. The keys or wedges are 60 then driven, thus binding and securing the rails firmly in position. The keys or wedges are secured by pins L, driven vertically through their ends.

By the modification shown in Fig. 6 of the 65 drawings, I dispense with the staples G and provide the top flange or head of the rail, in in lieu thereof, with transverse recesses or grooves M, having overhanging flanges N. The operation of this modification is obvious.

I claim as my invention and desire to secure by Letters Patent of the United States—

The combination of the metallic cross-ties, constructed substantially as described, the staples having flanges on their upper inner sides, 75 the rails, the wedge-shaped keys adapted to fit under the flanges of the staples, and having rabbeted sides to receive the rail-flanges, and the vertical fastening-pins driven through the ends of said keys, substantially as and for the 80 purpose set forth.

In testimony that I claim the foregoing as my own I have hereto affixed my signature in presence of two witnesses.

HENRY F. FLICKINGER.
